UNITED STATES PATENT OFFICE

WILLIAM M. KELLY, OF WESTFIELD, NEW JERSEY, ASSIGNOR TO AMERICAN TYPE FOUNDERS COMPANY, OF JERSEY CITY, NEW JERSEY, A CORPORATION OF NEW JERSEY

RECIPROCATING BED MOTION FOR PRINTING PRESSES

Application filed May 4, 1929. Serial No. 360,584.

The present invention relates to gearing and is more particularly concerned with that type of gearing which is used to reciprocate the bed of a printing press.

5 The primary object of the invention is the provision of gearing which is compact and easily handled, assembled and replaced, and in which lost motion and backlash is reduced to a minimum.

10 The reciprocating beds of printing presses are frequently driven from a common source of motive power through two distinct trains of gearing, one train serving to reciprocate the bed at a uniform rate of speed through

15 the major central portion of the stroke, and the other train operating to gradually retard, stop and reverse the motion of the bed at each end of the stroke in order to avoid abrupt reversal and consequent shock to the

20 bed frame and the driving gearing. This gearing is necessarily somewhat complicated and bulky and ordinarily occupies considerable space on either side of the bed and beneath the same, and unnecessarily increases 25 the lateral dimension of the space required for installation and the difficulty of providing proper support for the heavy and rapidly moving parts of the press.

It is therefore a feature of the present 30 invention to materially reduce the overall width of the driving gearing beneath and laterally of the bed, and to so arrange the component parts of the gearing as to evenly distribute the weight of the moving parts on 35 the supporting frame.

A more specific object of the invention is the provision of a direct uniform drive for the bed in the direction of execution of the printing stroke to eliminate backlash and 40 irregularity of motion and the resulting slurring of the printed sheet.

It is found that the use of upwardly facing racks in gearing of this character is undesirable, since the accumulation of paper 45 and other material falling from the moving parts of the press on the exposed rack causes jamming of the gearing and consequent breakage and delay in operation. It is therefore a further object of this invention to provide a gearing in which the use of such racks,

or of any similar toothed non-rotating parts, is avoided.

A further object of the invention is the provision of a novel form of alternating rotary gearing which is featured by lightness, compactness and simplicity of construction.

Further objects and features of the invention will be apparent from the following specification taken in connection with the 60 accompanying drawings, in which

Figure 1 is a front elevation of a preferred form of the gearing which constitutes the subject matter of the present invention;

Figure 2 is an end view of the gearing shown in Figure 1 with parts of the supporting frame removed to simplify the illustration;

Figure 3 is a section on the line 3—3 of Fig. 2, and

Figure 4 is a section on the line 4—4 of Fig. 2.

The invention is shown for the purpose of illustration in connection with a printing press of the two revolution type having the 75 usual impression cylinder 10 and the reciprocating bed 12, the specific construction of these elements forming no part of the present invention, which may be applied to the operation of presses of other types and to various other uses. A conventional feed board 13 and delivery mechanism 14 for the supply and removal of sheets to and from the press is shown in Fig. 2, and it will be understood that the cylinder is provided with the usual gripper and stripping devices, although the structural detail of these devices is immaterial for the purpose of illustrating the invention and has not been shown.

Referring now to Fig. 1, it will be seen that the gearing is carried principally by the spaced supports 14 and 15, which constitute the longitudinal side frame members of the press. The cylinder 10 is journaled in a conventional manner in supporting castings indicated generally at 18 and 19 which are in turn mounted on and bolted to or otherwise secured to the spaced supports 14 and 15. For convenience in illustration, the manner of supporting the bed 12 is not illustrated here.

in, although it will appear from the subsequent description of the invention that the component parts of the gearing are so arranged as to permit the provision of a solid central girth under the line of impression.

The gearing for reciprocating the bed is preferably driven from a common source of motive power associated with the pinion 16. This pinion meshes with a gear 17 which is in turn connected for rotation with the gear 20 through a shaft 23. The gearing so far described is conventional and may obviously be modified as desired.

The main drive of the machine, which effects the reciprocation of the bed through the central major portion of the stroke will now be described. As illustrated in Fig. 1 of the drawings, this drive comprises the element 21 which is provided with an annular externally toothed portion 22 in mesh with the gear 20 and adapted to be driven thereby. The element 21 is carried by and keyed or otherwise secured to the shaft 25 which extends transversely across the frame of the press and is journaled in the spaced supports 14 and 15 on either side thereof for a purpose to be described hereinafter.

As pointed out above, one feature of the present invention is the provision of gearing having a minimum width laterally of the press, and in the preferred construction, a pair of segmental internally toothed portions 27 and 28 are provided on the member 21, these toothed portions being disposed within the externally toothed portion 22 and being spaced axially of the shaft A for movement in adjacent planes perpendicular to the shaft. These toothed portions are preferably formed separately and bolted to the interior of the member 21 for ease in manufacture, assembly and replacement, although it is obvious that the teeth may be formed directly in the member 21 if desired. A gear 30 mounted on and secured to shaft 32 is positioned to engage and mesh with the internal toothed portion 27 and a gear 33 secured to the shaft 34, and spaced axially of the gear 30, is adapted to mesh with the internally toothed portion 28. As will be apparent from the drawings, the relative circumferential position of toothed portions 27 and 28 and of the gears 30 and 33, and the length of the toothed portions is such that the gears 30 and 33 are alternately and consecutively engaged by the segmental toothed portions to drive the gears alternately in opposite directions. The length of the toothed portions 27 and 28 is such that there is a distinct hiatus in the driving action between the periods of driving the respective gears, and this interval permits the reversing mechanism for slowing, stopping and accelerating the bed to come into play, the action of this mechanism being hereinafter described.

Shafts 32 and 34 are extended transversely

of the bed and are provided, preferably adjacent the central portion of the bed, with a pair of intermeshing gears 37 and 38, which are keyed or otherwise secured respectively to the shafts 32 and 34. It will be seen that by reason of this connection between the shafts, the gear 37 will be driven alternately in opposite directions by the successive action of the segmental toothed portions 27 and 28 on the member 21.

The reciprocation of the bed is obtained by the provision of a rack 40 extending longitudinally thereof and secured thereto, this rack being so disposed as to constantly mesh with the gear 37.

It will be seen that the width of the gearing required in this construction is only slightly greater than the total width of the two gear faces of the gears 30 and 33 so that a compact reversing gearing having a minimum of overhang outside of the bed frame is provided, and the wear on the bearings which support this gearing is thereby materially reduced. It will also be observed that the member 21 may be rotated in such a direction as to drive the bed directly through the shaft 32 during the execution of the printing stroke, the return stroke being executed through the shaft 34 and intermediate gear 33, thus reducing the backlash and lost motion to a minimum and eliminating slurs in the printing, this arrangement constituting an important feature of the present invention.

It is customary in presses of the two revolution type to provide for the elevation of the cylinder during the reverse idle stroke of the bed. The precise construction of this elevating mechanism forms no part of the present invention and is therefore not illustrated, but provision is made for driving the cylinder in a simple and direct manner and for allowing continuous and uniform rotation of the printing cylinder regardless of the position which it occupies. This function may be effectively performed in the present construction by the provision of a gear 45 suitably journaled on the casting 19 and connected for rotation with the cylinder 10 by a coupling permitting lateral displacement of the cylinder. As illustrated in Fig. 2, this coupling may take the form of a pin 47, carrying a block 48, mounted on the cylinder 10, and an arm 49 provided with a slot 50 and carried by the gear 45, the block sliding in the slot to permit displacement of the cylinder. By means of this construction, the cylinder may be continuously driven directly from the toothed member 21 and a uniform rate of rotation of the cylinder is thereby insured. The direct drive for the cylinder thus eliminates backlash and other inaccuracies existing in the driving connections between these elements. It will be noted that the diameter of the member 21 is consider-

ably greater than the diameter of the gear 45 which is driven thereby, and the effect of the relative sizes of these gears in further reducing backlash will be readily understood.

As pointed out hereinbefore, it is essential to provide a reversing mechanism for the bed, operative at each end of the stroke, the parts of which are so constructed and arranged as to avoid the accumulation of paper and other material in the toothed portions of the mechanism, and consequent injury to the press. The preferred form of this reversing mechanism is shown in Fig. 2 of the drawing, in which a pin 60 carrying a block 61 is provided on the gear 17. A cross head 64 having a slot 65 disposed transversely thereof is slidably supported in any suitable manner. It will be seen that this mechanism constitutes a form of the conventional Scotch yoke, and results in imparting substantially harmonic reciprocation to the cross head 64.

A pair of toothed racks 68 and 69, which are secured to the under side of the bed and are preferably removable therefrom and adjustable lengthwise of the bed, are adapted for engagement at each end of the bed stroke with an element 71 having a segmental toothed portion 73 for meshing with the racks. In order to conserve space, and to restrict the gearing to the central portion of the press, the element 71 is fulcrumed on a stationary shaft for pivotal movement about an axis beneath the shaft 32, which carries the gears 37 and 30. This shaft 32 also preferably carries the pinions 35 and 36 which serve to reciprocate a set of rollers on which the bed is supported, in the manner disclosed in the prior patent to Kelly 1,651,744, granted December 6, 1927. This mechanism is omitted from the present disclosure for the sake of clearness. For this purpose the shaft 32 extends transversely of the bed from the driving side, where it is journalled in the support 15 to a point on the further side of the central portion of the bed. It is therefore necessary to provide for the oscillation of the element 71 without interference by the shaft 32, which may be conveniently arranged by providing forked arms 78 and 79 on the element 71, embracing the shaft 32, and by removably securing the toothed segment 73 across the fork ends. This construction not only has the advantage of extreme simplicity and compactness, but also provides for ready assembly, removal and replacement of the segment 73. An arm 81 is secured to or formed integrally with the member 71 and extends below the axis of the bearing support 72 so that this member in effect constitutes a two armed lever. A link or pitman 83, pivotally connected at its ends to the cross head 64 and to the arm 81 respectively, serves to transmit the movement of the cross head to the member 71 for imparting substantially harmonic reciprocation to the latter.

The general operation of the device will be obvious from the foregoing description and from the drawings. The central major portion of the stroke of the bed is effected through the train of gears 16, 17, 20, 22, and 70 through either of the trains 27, 30, 37 and 40, or 28, 33, 38, 37 and 40, to drive the bed uniformly in opposite directions. The reversal of the bed at the ends of the stroke is effected through the gear 17, cross head 64, link 83, 75 lever 71, segment 73 and either of the racks 68 or 69, the last mentioned train serving to receive the bed at its maximum speed, gradually retard and stop the bed and to gradually accelerate the bed in the reverse direction. 80

As pointed out above, the shaft 25 extends transversely across the frame and through the spaced supports 14 and 15, one end of the shaft carrying the member 21, and the other end thereof carrying the cam 85. This cam serves to oscillate a lever 86 pivoted at 87 to the frame and connected at its opposite end 88 to a suitable mechanism for operating the conventional grippers. It is extremely important to eliminate backlash 90 and lost motion in the connection between the driving mechanism for the bed and cylinder and the gripper operating mechanism, and it will be seen that the desired result is accomplished in the present instance by directly connecting the main driving element of the bed motion with the gripper operating cam. 95

It will be apparent from the above description that the present construction offers decided advantages in compactness and simplicity, and while the invention is preferably constructed in accordance with the accompanying drawings, various changes and substitutions may be effected therein as fall within the spirit and scope of the appended claims. It will furthermore be obvious that the gearing disclosed herein is adapted for other uses and will perform other functions than those herein enumerated, and is not confined to use with the two revolution press which has been shown for the purpose of illustrating the invention. 110

Having thus described the invention, what is claimed as new and desired to be secured by Letters Patent is:

1. In gearing, the combination with a driving gear, of a rotatable element having external teeth in mesh with said driving gear and having two segmental internally toothed portions acting in different planes spaced axially of the element, a driven gear, a gear rotatable with said driven gear and adapted to be engaged by one of said toothed portions, a gear adapted to mesh with the other of said toothed portions, and means for driving said driven gear from said last mentioned gear in a direction opposite thereto, the said toothed portions and the gears meshing therewith being so disposed that not more 120

than one of said toothed portions is in engagement with the corresponding gear at any given time, whereby the driven gear may be rotated in alternately opposite directions on 5 rotation of said driving gear in one direction.

2. In gearing, the combination with a driving gear, of a rotatable element having external teeth in mesh with said driving gear and 10 having two segmental internally toothed portions acting in different planes spaced axially of the element, a driven gear, a gear rotatable with said driven gear and adapted to be engaged by one of said toothed portions, an 15 intermediate gear meshing with said driven gear, and a gear rotating with said intermediate gear and adapted to mesh with the other of said toothed portions, the said toothed portions and the gears meshing therewith 20 being so disposed that not more than one of said toothed portions is in engagement with the corresponding gear at any given time, whereby the driven gear may be rotated in alternately opposite directions on 25 rotation of said driving gear in one direction.

3. In a printing press having an impression cylinder and a reciprocating bed adapted to execute a forward printing stroke and 30 a reverse idle stroke, the combination with a toothed rack secured to said bed, of means for driving said rack and bed in alternately opposite directions, said means including a gear meshing with said rack, an intermediate gear meshing with said first mentioned gear, a pair of gears secured for rotation with 35 said first mentioned gear and said intermediate gear respectively, a pair of toothed segments each of which is adapted to mesh with one gear of said pair of gears and positioned 40 for consecutive engagement therewith, and means for driving said toothed segments in the same direction for imparting the forward printing stroke to said bed directly through 45 said first mentioned gear, and for imparting the reverse idle stroke to said bed through said intermediate gear.

4. In a printing press having an impression cylinder and a reciprocating bed adapted 50 to execute a forward printing stroke and a reverse idle stroke, the combination with a toothed rack secured to said bed, of means for driving said rack and bed in alternately opposite directions, said means including a gear meshing with said rack, an intermediate gear meshing with said first mentioned gear, a pair of gears secured for rotation with said 55 first mentioned gear and said intermediate gear respectively, a rotatable driving element having a pair of segmental toothed portions each of which is adapted to engage and drive one of said pair of gears, the periods of driving engagement being consecutive, and means for rotating said driving element in a 60 direction to impart the forward printing

stroke to said bed directly through said first mentioned gear, and to impart the reverse idle stroke to said bed through said intermediate gear.

5. In a printing press having an impression cylinder and a reciprocating bed adapted to execute a forward printing stroke and a reverse idle stroke, the combination with a toothed rack secured to said bed, of means for driving said rack and bed in alternately opposite directions, said means including a gear meshing with said rack, an intermediate gear meshing with said first mentioned gear, a pair of gears secured for rotation with said first mentioned gear and said intermediate gear respectively, a rotatable driving element having a pair of segmental internally toothed portions positioned to consecutively engage and drive a corresponding gear of said pair of gears and having an externally toothed portion encircling said internally toothed portions, and a gear meshing with said externally toothed portion for driving the latter in a direction to impart the forward printing stroke to said bed directly through said first mentioned gear, and to impart the reverse idle stroke to said bed through said intermediate gear.

6. In a reciprocating bed motion, the combination with a bed, of means for reciprocating said bed through the central portion of the stroke thereof in either direction, and means for reversing the direction of movement of the bed at one end of the stroke thereof, said last mentioned means comprising a toothed rack carried by said bed, a lever of the first class having a segmental toothed portion on one arm thereof adapted to mesh with said rack, and mechanism associated with the other arm for imparting substantially harmonic reciprocation thereto.

7. In a reciprocating bed motion, the combination with a bed, of means for reciprocating said bed through the central portion of the stroke thereof in either direction, and means for reversing the direction of movement of the bed at one end of the stroke thereof, said last mentioned means comprising a toothed rack carried by said bed, a lever of the first class having a segmental toothed portion on one arm thereof adapted to mesh with said rack, and mechanism associated with the other arm for imparting substantially harmonic reciprocation thereto, said mechanism including a Scotch yoke, 120 and a pitman connecting said yoke and said other arm.

8. In a reciprocating bed motion, the combination with a bed, of means for reciprocating said bed through the central portion of the stroke thereof in either direction, and means for reversing the direction of movement of the bed at both ends of the stroke thereof, said last mentioned means comprising rack teeth carried by said bed, a mem- 130

ber provided with a segmental toothed portion adapted to mesh with said rack teeth, a continuously rotating crank, a crosshead mounted for reciprocation in a straight line transversely of the axis of said crank and having a slidable connection therewith, and means connecting said member and said crosshead.

9. In a printing press having an impression cylinder and reciprocating bed, the combination with a frame including spaced supports on which the cylinder is journaled at each end thereof, of a pair of racks secured beneath said bed and extending longitudinally thereof, a gear meshing with one of said racks for reciprocating said bed through the central portion of the stroke, a shaft on which said gear is mounted extending transversely of the frame, and an oscillating arm mounted 20 below the transversely extending shaft and provided with a segmental toothed portion meshing with the other of the said racks for reversing the direction of movement of the bed at the end of the stroke, said arm being 25 slotted to receive the shaft.

10. In a printing press having an impression cylinder and reciprocating bed, the combination with a frame including spaced supports on which the cylinder is journaled at each end thereof, of a pair of racks secured beneath said bed and extending longitudinally thereof, a gear meshing with one of said racks for reciprocating said bed through the central portion of the stroke, a shaft on which 30 said gear is mounted extending transversely of the frame, a forked oscillating arm mounted beneath and embracing the transversely extending shaft, and a toothed segment removably secured across the fork ends of the 35 arm and above the shaft for engaging the other of the said racks to reverse the direction 40 of motion of the bed at the end of the stroke.

11. In a printing press having an impression cylinder, a reciprocating bed, and cam operated gripper mechanism, the combination with a frame including spaced supports on which the cylinder is journaled at each end thereof, of a shaft extending transversely across the frame and journaled adjacent each 50 end thereof in the spaced supports, a gear secured on one end of said shaft outside of the frame and operatively connected with said cylinder to drive the latter, and a gripper operating cam secured to the opposite end of 55 the shaft outside of the frame.

12. In a printing press having an impression cylinder, a reciprocating bed, and cam operated gripper mechanism, the combination with a frame including spaced supports 60 on which the cylinder is journaled at each end thereof, of a shaft extending transversely across the frame and journaled adjacent each end thereof in the spaced supports, a gear secured on one end of said shaft outside of 65 the frame and operatively connected with

said cylinder to drive the latter, a gripper operating cam secured to the opposite end of the shaft outside of the frame, internally toothed segmental gears secured to said first mentioned gear, and means driven by said segmental gears for driving the bed in alternately opposite directions. 70

13. In a printing press having an impression cylinder, a reciprocating bed, and cam operated gripper mechanism, the combination with a frame including spaced supports on which the cylinder is journaled at each end thereof, of a shaft extending transversely across the frame and journaled adjacent each end thereof in the spaced supports, a gear secured on one end of said shaft outside of the frame, a second gear journaled on the frame and meshing with said first mentioned gear, a coupling between said second gear and said cylinder permitting lateral displacement of 80 the latter, and a gripper operating cam secured to the opposite end of the shaft outside of the frame. 85

14. In a reciprocating bed motion, the combination with a bed having a toothed rack portion, of a driving gear, a rotatable element having external teeth in mesh with said driving gear and having two segmental internally toothed portions acting in different planes spaced axially of the element, a driven gear 90 adapted to mesh with said rack, a gear rotatable with said driven gear and adapted to be engaged by one of said toothed portions, a gear adapted to mesh with the other of said toothed portions, and means for driving said driven gear from said last mentioned gear in a direction opposite thereto, the said toothed portions and the gears meshing therewith being so disposed that each of said toothed portions is brought alternately into engagement 95 with the corresponding gear, whereby the driven gear may be rotated in alternately opposite directions on rotation of said driving gear in one direction to drive the bed in alternately opposite directions, and mechanism for reversing the direction of movement of the bed at each end of the stroke thereof, said mechanism comprising a pair of toothed rack sections secured to the bed at spaced points, a gear segment adapted to mesh alternately 100 with said rack sections, and means for reciprocating said gear segment. 105

15. In a reciprocating bed motion, the combination with a bed having a toothed rack portion, of a driving gear, a rotatable element 110 having external teeth in mesh with said driving gear and having two segmental internally toothed portions acting in different planes spaced axially of the element, a driven gear adapted to mesh with said rack, a gear rotatable with said driven gear and adapted to be engaged by one of said toothed portions, a gear adapted to mesh with the other of said toothed portions, and means for driving said driven gear from said last mentioned gear in 115 120 125 130

a direction opposite thereto, the said toothed portions and the gears meshing therewith being so disposed that each of said toothed portions is brought alternately into engagement with the corresponding gear, whereby the driven gear may be rotated in alternately opposite directions on rotation of said driving gear in one direction to drive the bed in alternately opposite directions, and mechanism for reversing the direction of movement of the bed at each end of the stroke thereof.

16. In a reciprocating bed motion, the combination with a bed, of gearing for driving said bed in alternately opposite directions through the major portion of the stroke thereof, a rotatable element provided with an annular toothed portion and with a pair of segmental toothed portions for actuating said gearing, mechanism for reversing the direction of movement of the bed at the ends of the stroke, a pinion meshing with the said annular toothed portion of said rotatable element, and a crank pin carried by the said pinion and operatively connected to said reversing mechanism for actuating the latter.

17. In gearing, the combination with a rotatable element having two segmental internally toothed portions acting in different planes spaced axially of the element, a driven gear, a gear rotatable with said driven gear and adapted to be engaged by one of said toothed portions, a gear adapted to mesh with the other of said toothed portions, and means for driving said driven gear from said last mentioned gear in a direction opposite thereto, the said toothed portions and the gears meshing therewith being so disposed that not more than one of said toothed portions is in engagement with the corresponding gear at any given time, whereby the driven gear may be rotated in alternately opposite directions on rotation of said driving gear in one direction.

18. In a printing press, the combination with a reciprocating bed, of a frame including side members for supporting said bed, bearings in one of said side members, a pair of rotatable shafts extending through said bearings, means carried by said shafts and located within said frame for driving the bed, and gearing outside of the frame for driving said shafts, said gearing including a pair of axially spaced gears, one of which is mounted on each shaft, a member journaled in said side member having a pair of segmental internally toothed portions adapted to mesh alternately with said gears and having an externally toothed portion encircling said internally toothed portions, and a gear meshing with the externally toothed portion of said member to drive the latter in one direction, the total width of the gearing externally of the bed frame being only slightly greater than the width of two gear

faces, whereby the overhang of the shafts and consequent wear on the bearings is minimized.

In testimony whereof I hereunto affix my signature.
